UNITED STATES PATENT OFFICE.

MARY CHASE WITHERBEE, OF WEST NEWTON, MASSACHUSETTS.

EGG-BEATER.

1,250,539.

Specification of Letters Patent. Patented Dec. 18, 1917.

Application filed March 31, 1916. Serial No. 87,929.

To all whom it may concern:

Be it known that I, MARY CHASE WITHERBEE, a citizen of the United States, residing at West Newton, in the county of Middlesex and State of Massachusetts, have invented certain new and useful Improvements in Egg-Beaters; and I do hereby declare the following to be a full, clear, and exact description of the invention, such as will enable others skilled in the art to which it appertains to make and use the same.

My invention relates to "egg-beaters." That is, to devices for beating eggs or other material. Its object is to provide a beater which shall, in accordance with the familiar practice of the housewife, "beat up" the egg or other material from the bottom upward and also shall beat or drive the material in the same direction throughout the operation. To this end it comprises the combinations of parts recited in the appended claims.

In the drawings:

Figure 1 is a front elevation; Fig. 2 is a side elevation of a part of the sleeve;

Fig. 3 is a sectional detail looking down upon the main whisk or beater; and

Fig. 4 is a detail cross section of the main whisk or beater.

I have found, contrary to the usual practice with egg-beaters, that to accomplish the desired purpose, that is, to beat the material so that it is light, it should be beaten upward and not merely whirled around, and that as much air as possible shall enter the material while being treated. I have discovered also that the material should be beaten in the same direction throughout the operation and not by means of two instruments operating in opposite directions as in the customary egg-beater.

In the drawings, 10 represents the customary handle to which is secured a drive wheel 11 with a handle attachment 12, it not being deemed necessary to illustrate the familiar driving handle in this case. I have also indicated, rather than illustrated, an idler 13 lying behind the handle-iron and engaging the driving gear-wheel.

It would be feasible to have the handle rod run beyond the driving wheel and rest upon the bottom of the vessel holding the material to be treated. I prefer, however, to follow the familiar custom and provide a separate cast arm which enters the handle

10 and which bears the axis for the driving gear-wheel. At the bottom is secured to this bearing casting, preferably by a set screw as illustrated, a separate shaft 100. 60

Surrounding this shaft 100 is a sleeve 14 which rests as indicated on a shoulder on the bottom of the shaft and which carries at the top a driving pinion 15. It is obvious that through the handle the driving gear 65 may be rotated, being guided in its movement by the idler 13 while it rotates the gear wheel 15 and thus rapidly rotates the sleeve. These parts are familiar and my invention resides in the arrangement of the whisks 70 or beaters on the sleeve.

I have illustrated on opposite sides of the sleeve two reversely arranged whisks or beaters 16, 17, which, in my preferred form, have a backing of a curved rod attached at 75 the top in any manner to the sleeve and at the bottom to a vertical rod, 18, 19, one on each side of the shaft, parallel with the sleeve and secured thereto at the top, as for example, by a short sleeve. Each of these 80 curved rods, 16, 17, has a substantially spoon-shaped plate 20, 21, extending out and preferably bent slightly at the outer edge 22, 23, so that it will extend down toward the bottom of the receptacle in which the material 85 is contained. In cross section the spoon-plate is roughly ogee shaped, as indicated in the cross section shown in Fig. 4. Within the outer whisks are placed bent rod beaters 24 and 25, 26 and 27, which stand out from 90 the sleeve on opposite sides in reverse directions, preferably, as illustrated, and which are arranged so that the several beaters project also outward through a plane beyond the sleeve. Broadly, as shown in Fig. 3, 95 what may be termed the backward curve is on the curved plane which would follow the outer curve of the inner beater. I have also found it advantageous to arrange these in series so that the inner one of the beater 100 rods shall project into a plane the farthest beyond the plane of the sleeve, the second one somewhat inside the outer line, and the third rod carrying the spoon-shaped part still farther within the line and nearly within a plane corresponding with the outer wall 105 of the sleeve.

In the operation of the beater the material is rotated in one way only and while the outer layers are thus rotated the lower layer 110 is also rotated and at the same time thrown up into the rotating mass, this action per-

mitting the air to enter and at the same time permitting the action to be rapid and effective.

It is obvious that these relative arrangements of the whisks or beaters may vary considerably but I am here describing and illustrating the form which I have found preferable in practice, and which I have found best meets the conditions required to 10 rotate a liquid or plastic material in one direction while at the same time beating it upward. It is also obvious that I use the term "egg-beater" in the specification and the succeeding claims merely as a convenient 15 designation of my device which may be employed to treat various materials.

I claim:

1. In an egg-beater or similar device, the combination with a handle, shaft and operat-

ing parts, of whisks or beaters curved outwardly and also curved in different planes with reference to the shaft, and arranged in reverse order on opposite sides of the shaft. 20

2. In an egg-beater or similar device, the combination with a handle, shaft, carrying 25 sleeve and operating parts, of whisks or beaters comprising reversely arranged curved rods substantially ogee-shaped each bearing a substantially spoon-shaped plate extending outwardly and downwardly and 30 a series of curved beaters above the plate-bearing beaters, standing out on opposite sides in reverse directions and arranged so that the several beaters project outward through a plane beyond the sleeve. 35

In testimony whereof I have hereunto signed by name.

MARY CHASE WITHERBEE.
